L. A. SCHWAN

REFEREE'S STAND

Filed May 4, 1926

Inventor
Louis A. Schwan

By Spear, Middleton, Donaldson, Hall

et al.

UNITED STATES PATENT OFFICE.

LOUIS A. SCHWAN, OF FORT WAYNE, INDIANA, ASSIGNOR TO A. G. SPALDING & BROS., OF NEW YORK, N. Y., A CORPORATION OF NEW JERSEY.

REFEREE'S STAND.

Application filed May 4, 1926. Serial No. 106,663.

My present invention relates to a referee's stand, such as may be used particularly with 5 volleyball, although the invention is not limited thereto, as the same may be readily used in any analogous game such as basket ball, for instance.

The principal object of the invention is the provision of a stand which may be used to elevate the referee to a point where he 10 can readily overlook the floor upon which the game is played and correctly judge the same.

Another important object is the provision of such a stand as above which will be simple to construct, of a strength sufficient to make the device efficient, and yet which may be easily and quickly folded into a compact package for transportation or to a place of storage when the stand is not being used.

20 To this end the invention includes a platform upon which the referee may stand supported at its front and rear portion by legs hinged to the bottom of the platform, two of the legs supporting the platform forming 25 a ladder so that the referee may readily mount to his position, and the platform having at one end risers approximately waist high above the platform, with a guard rail attached thereto serving to keep the 30 referee from accidentally falling from the platform.

The invention further includes the novel construction, arrangement and combination of parts hereinafter shown and described in 35 the accompanying drawings.

I have illustrated a preferred embodiment in the drawings in which

Figure 1 is a side elevation of one form of the device.

40 Fig. 2 is a front elevation.

Fig. 3 is a plan view.

Fig. 4 shows the device folded.

Referring now with particularity to the drawings, I have indicated at 1 the platform 45 upon which the referee may stand, which consists of battens 2 having boards 3 secured thereto so as to form a natural platform.

Hinged to the rear of the platform 1 as 50 by means of the hinges 4, I provide a ladder which consists of the legs 5 and steps 6 in the usual manner. It is to be noted that the boards 3 comprising the platform 1 rest on top of the legs 5 and the hinges 4 em-

brace both the ends of the boards 3 and the legs 5.

Towards the front of the platform 1 I provide hinges 7 which attach the same to front legs 8 having attached thereto brace 9 to give support to the same. It is to be noted that the hinges 7 are attached to the 60 inside of the legs 8 and the underside of the boards 3.

A lower platform, comprising battens 10 and surface boards 11, is articulated to the legs 5 as by means of hinges 12, the legs 5 65 being provided with cut-away portions as at 13 within which portions the lower platform 11 is adapted to fold when the device is not in use. When in use this lower platform rests upon the shoulders formed by the cut-away portions 13 in the legs 5, and the brace 9 in the legs 8. A brace is provided comprising a rod 14 having a right angular portion 15 penetrating the leg 8 and held therein by means of a cotter pin 16, and a longer 70 bent rod 17 connected to the rod 14 as by means of a turn buckle 18. The legs 5 are provided with apertures 19 into which the bent ends 20 of the rods 17 are adapted to seat. In this position it will be noted that 75 the brace effectively prevents the structure from collapsing, as it provides in effect a diagonal brace between the two sets of supporting legs.

Secured at the front of the referee's platform 1 I provide upstanding parts or standards 21 pivotally secured to the said platform as by means of hinges 22 so that the device may be folded in a manner as will be more fully described hereinafter. A rod 90 23 connects the upper ends of these parts and extends beyond the same as at 24. These extensions 24 are adapted to have connected thereto a member 25 designed to sustain the stand against the pull of the 95 net, which sustaining member is preferably of substantially U-shape so as to enclose the referee when standing on the platform and prevent his accidentally stepping off the same. The ends of the sustaining member 100 are provided with eyes which engage the extended ends 24 of the rod 23. Pins 26^a are provided to prevent the ends 26 from accidental removal from the extended ends 24 of the rod 23. The enclosing member 105 24 extends towards the rear of the platform

and beyond the portion on which the referee is to stand, and terminates in a loop 27, which may be used to receive a rope, cable, or the like, the other end of which may be attached to the wall of the gymnasium, or to a stake in the ground when the game is to be played out-of-doors.

At approximately the center of the rod 23 I provide a ring 28 which is adapted to receive one end of the upper reach of the volleyball net, the other end to be attached to a similar stand at the other end of the court or floor. The lower reach of the net is adapted to attach to the ring 29 secured in the upper support 9 in the front legs 8.

In folding the device, the supporting ropes and net having been removed, the enclosing member 25 may be pulled backward towards the steps which will fold the uprights 21 down flat on to the referee's platform, the part 25 extending down the steps. The lower ends of the braces are then removed from the sockets in the legs 5 whereupon the legs 8 may be collapsed against the legs 5. As this is done, the lower supporting platform 11 folds into the cut-away portions on the legs 5, so that the

entire stand is readily foldable into a compact package for transportation or storage, as may be desired.

I claim:

1. A folding referee's stand comprising a platform, two sets of legs hinged to opposite sides of said platform for supporting the same, steps upon one set of legs forming a ladder, and a lower platform hinged to one set of legs and having its free edge engageable with the other set of legs, said first named set of legs having cut away portions into which said lower platform may be folded.

2. A folding referee's stand comprising a platform, two pairs of legs articulated to opposite edges of said platform, detachable and folding bracing means for said pairs of legs, uprights hinged to the platform at one edge thereof and foldable down upon the top of the platform, and a member hinged to said uprights and adapted to be connected to a fixed support to prevent tipping of the stand.

In testimony whereof, I affix my signature.

L. A. SCHWAN.
